UNITED STATES PATENT OFFICE.

JOHN HUME BELL, OF SOUTH ORANGE, NEW JERSEY, ASSIGNOR TO WESTERN ELECTRIC COMPANY, INCORPORATED, OF NEW YORK, N. Y., A CORPORATION OF NEW YORK.

TELEGRAPH SYSTEM.

Application filed April 17, 1922. Serial No. 553,720.

To all whom it may concern:

Be it known that I, JOHN H. BELL, a citizen of the United States, residing at South Orange, in the county of Essex, State of New Jersey, have invented certain new and useful Improvements in Telegraph Systems, of which the following is a full, clear, concise, and exact description.

This invention relates to telegraph systems and particularly to repeating apparatus for such systems.

An object of the invention is to provide repeating means intermediate the sections of a line conductor for repeating impulses from one line section to another and in which the false operation of the repeating means is prevented following the transmission of a signaling impulse.

Another object is the provision of means to prevent the false operation of the telegraph sounder following the transmission of a signaling impulse.

In telegraph systems utilizing repeating apparatus where the telegraph impulses are transmitted by means of the open circuit Morse system over lines having considerable electrostatic capacity, there is a tendency for the recording sounder to give false indications due to the capacity discharge of the line affecting the home station relay which should remain inoperative following the operation of its associated transmitting equipment.

The invention provides an arrangement of apparatus at both the terminal and repeater stations, whereby following the transmission of an impulse to line, the polarity of the charge of the distributed capacity is such as to prevent the false operation of the apparatus located at the respective stations.

There is shown in the drawing, two line sections 4 and 5, extending from terminal stations X and Y respectively, to a repeater station A where apparatus is located for repeating impulses from one line section to another which will be free from bias and distortion. Connected with each of the line sections is a transmitting key which serves to connect the line with a source of battery for causing the operation of the receiving apparatus at the opposite end of the line through the instrumentalities of the repeater equipment located at the repeater station

A. Serially connected with a contact on the transmitting key is what is usually referred to as the home station relay which controls, through its contacts, the actuation of a sounder for giving to the operator an audible indication of the character of the impulse transmitted from the distant station.

The equipment located at the repeater station A comprises a pair of polarized relays having two coils, one serving as an operating coil, while the other functions to normally maintain the line section with which it is associated extended to the operating coil of the relay associated in the other line section. The latter mentioned coil is normally energized from a local source of battery through an adjustable resistance thereby permitting of the variation of the current through its winding or, in other words, making it possible to increase the bias and to adjust it over a wide range.

The home station relay like the relays at the repeater station, is provided with an operating, and what may be termed a spacing coil, the former of which serves to close the energizing circuit of the recording sounder, while the other maintains the circuit of the sounder open during the non-operation of the system. Likewise, the latter coil is maintained energized by current furnished from a local battery through an adjustable resistance in order that the bias may be adjusted through a wide range, thus eliminating the use of biasing springs.

Owing to the characteristics of signaling conductors, especially those used for cable work, possessing considerable electrostatic capacity as represented by the condensers shown dotted, upon the impression of a signaling impulse on the line conductor, the conductor becomes charged and upon the restoration of the transmitting key to normal, this charge tends to leak off through the winding of the home station relay thereby causing its false operation. However, such objection is obviated by the use of polarized relays, as previously described, and by having the batteries at the respective terminals of opposite polarity. With this arrangement, the discharge currents from the electrostatic capacity of the line in passing through the home station relay will tend to

make it space, that is, to maintain the circuit of the recording sounder open, thus preventing its false operation.

The operation of the system just described 5 is as follows:

Assume that it is desired to transmit message impulses from the station X to the station Y. Upon the depression of the key 6, the source of battery 20 is connected with 10 the terminal of the line section 4. Current thus transverses the line section 4 and passes through the coil 16 of the repeating relay associated with the line section 5. Current in passing through the coil 16 causes its 15 energization thereby applying the positive polarity of battery 26 to the line section 5, this current in passing over this line section, traverses the normally closed contact of the key 24 and the winding of the coil 22. Upon 20 the energization of the winding of the coil 22, the armature controlled thereby will be attracted for closing the circuit of the recording sounder thereby causing its operation to give an audible indication to the operator. During the time that the key 6 is 25 depressed and the battery 20 is associated with line section 4, the distributed electrostatic capacity will be charged of a polarity in accordance with the polarity of the battery 20 and the electrostatic capacity of line 30 section 5 will be charged of a polarity in accordance with the polarity of the battery 26. Upon the restoration of the key 6 and the repeating relay associated with the line section 35 4 to normal, the current generated by the discharge of the electrostatic capacity in line section 4 tends to pass through the coil 8 of the home station relay 7, and that in line section 5 through the coil 12 of the repeating relay associated with the line section 5. In the present system, however, the current 40 passing through coil 8 will produce the same magnetic action as coil 9 and the current in coil 12 will produce the same magnetic action as coil 13. Thus, the discharge of the 45 distributed electrostatic capacity will have no effect upon the home station and repeater station relays and the operator will receive no false indication due to such discharge. 50 Likewise, when the key 24 at the station Y is depressed for the transmission of message impulses, the coil 12 of the repeating relay associated with the line section 4 will be actuated for applying to the line section 4

an impulse in accordance with the depression 55 of the key 24. The armature of this relay will, however, be restored to its normal condition due to the action of the coil 13 on the associated armature, which has normally applied thereto the battery from the source 60 14 through the adjustable resistance 15 upon the restoration of the key 24 to normal.

Although the invention has been shown in connection with one specific form of telegraph system, it is, of course, obvious that 65 it may be applied to other types of systems without departing from the spirit and scope of the present invention.

The invention claimed is:

1. A telegraph system provided for open 70 circuit operation, a line conductor possessing considerable electrostatic capacity and divided into sections, repeating apparatus intermediate the line sections comprising polarized relays, current sources of opposite 75 polarity connected to the respective line sections by said relay, transmitting and receiving mechanisms associated with the terminal of each line section, means associated with said receiving mechanism for controlling its 80 operation, and circuit connections effective following the impression of an impulse on a line section and the operation of a polarized relay for rendering said means effective to prevent the receiving mechanism from giving 85 a false indication.

2. A telegraph system provided for open circuit operation, a line conductor possessing considerable electrostatic capacity and divided into sections, repeating apparatus intermediate said line sections comprising a pair of polarized relays, current sources of opposite polarity connected to the respective line sections by said relays, transmitting and receiving mechanisms associated with the 90 terminal of each line section, said receiving mechanism consisting of a home station relay and a recording sounder, and circuit connections effective following the impression 95 of an impulse on a line section and the operation of the repeating apparatus to cause the discharge of the electrostatic capacity of said line through a winding of said home station relay to insure the maintenance of its contacts open.

In witness whereof, I hereunto subscribe my name this 14th day of April A. D., 1922.

JOHN HUME BELL.
